UNITED STATES PATENT OFFICE.

LEWIS NICHOLAS, OF INDIANAPOLIS, INDIANA.

LOW-WATER-SIGNAL APPARATUS FOR STEAM-BOILERS.

1,376,966.

Specification of Letters Patent.

Patented May 3, 1921.

Application filed December 5, 1919. Serial No. 342,715.

To all whom it may concern:

Be it known that I, LEWIS NICHOLAS, a citizen of the United States, residing at Indianapolis, in the county of Marion and State 5 of Indiana, have invented a new and useful Low-Water-Signal Apparatus for Steam-Boilers, of which the following is a specification, reference being had to the accompanying drawings, and to the letters and figures 10 of reference marked thereon.

This invention relates to a locomotive type of steam-boiler or one provided with a metallic fire-box having a crown sheet exposed to intense heat and covered in operation by 15 water to be converted into steam, the invention having reference more particularly to an alarm signal and apparatus for automatically sounding an alarm, in case the water level becomes too low on the crown 20 sheet so that the crown sheet would be liable, with a further lowering of the level of the water, to be damaged by the heat in the fire-box, with a possible explosion and destruction of the steam-boiler, and possibly entail- 25 ing the loss of life.

An object of the invention is to provide an automatic safety signal designed to indicate to the engineer or attendant when a dangerously low level of water in the steam-boiler occurs, which may result when the 30 steam-boiler is not fed or is insufficiently fed with water.

Another object is to provide simple, positive and reliable means for sounding a low 35 water alarm when, because of operating noises, escaping steam might not be heard when a fusible plug in the crown sheet becomes melted, or in case a visible signal might not be observed.

40 A further object is to provide a low water signal apparatus for steam-boilers which shall be so constructed as to include means for stopping the escape of water or steam into the fire-box after a fusible plug has 45 melted, in order to prevent serious loss of water and permit further operation of the steam-boiler or continuance of a trip of the locomotive to destination when a new fusible plug may be supplied.

50 With the above-mentioned and other objects in view, the invention consists in a structure adapted to hold a fusible plug and provided with means for closing the aperture left when the plug is melted, the apparatus being adapted to automatically operate 55 an alarm device promptly when the fus-

ible plug is destroyed; and, the invention consists also further in the parts and combinations and arrangements of parts as herein-after particularly described and further defined in the accompanying claims.

Referring to the drawings,—Figure 1 is a fragmentary vertical section of a locomotive type steam-boiler and fire-box to which the invention is applied; Fig. 2 is a fragmentary sectional view of the steam-boiler and a central sectional elevation of the safety appliance on an enlarged scale; Fig. 3 is a view similar to that in the preceding figure but showing the signal operating device in 70 a different position permitting operation of the steam-boiler after the fusible element has been melted away; Fig. 4 is a top plan of one of the devices of the invention which assists in holding the fusible element in 75 position and affords means to permit operation of the boiler after disappearance of the fusible element; and, Fig. 5 is a side view of the fusible element as preferably constructed.

Similar reference characters in the different figures of the drawings indicate corresponding elements or features of construction herein referred to in detail.

In the drawings the numeral 1 indicates 85 the barrel, 2 the flue sheet, 3 the fire-box crown sheet, 4 the shell or outer sheet of the fire-box, 5 the boiler head, and 6 the rear end of the fire box of a familiar type of locomotive steam-boiler, in connection with which 90 is a cab having a front 7 extending over the shell 4 of the fire-box.

The improved safety appliance comprises 95 a plug 8 which is screw-threaded and inserted in a suitable opening in the crown sheet 3 and it has a relatively small neck 9 on its upper portion which is screw-threaded externally, the neck having a flat top 10; and, the plug has a bore 11 extending therethrough to receive fire-box heat. The upper 100 portion of the bore is closed by a suitably shaped piece of metal that is fusible at a degree of heat which may be determined upon as desirable to guard against overheating of the crown sheet. The fusible element 105 preferably is shaped as a disk 12 which is placed upon the top 10 of the plug and having a boss 13 on its top. A cylinder 14 is provided which has a cylindrical bore 15 extending from its top downward to an annular ledge 16 formed in the cylinder to constitute an annular valve seat which has an 110

opening 17 adapted to closely receive the boss 13, the ledge being adapted to engage the disk portion of the fusible piece and secure it in place, the cylinder having a chamber 18 in its lower portion which has internal screw-threads engaging the screw threads of the neck 9. The shell 4 is provided with a packing box 19 above the cylinder 14 and a valve stem 20 extends through 10 the packing box and into the bore 15 and has a piston valve 21 on its lower end that is movable in the cylinder 14 but is slightly less in diameter than the bore of the cylinder to permit water or steam to leak past the 15 piston valve, the under side of the latter having a valve face 22 adapted to engage the valve seat and close the opening 17 when the fusible piece is absent. Preferably the valve stem 20 has a stop collar 23 fixed thereon to 20 limit the upward movement of the valve stem when brought into contact with the under side of the packing box. The outer end of the valve stem 20 has a head 24 thereon which preferably is removable from the 25 stem. At a suitable distance from the packing box a standard 25 is secured to the shell 4 and pivotally supports a bell-crank having an arm 26 that is detachably connected with the head 24 and being horizontally extended, 30 the bell-crank having another arm 27 extending upwardly. A steam-whistle 28 is connected to the shell 4 so as to utilize steam from the steam-boiler and it has a suitable operating lever 29 to which a rod 30 is connected which is connected also with the bell-crank arm 27. The signal whistle shown is 35 of familiar type but may be variously constructed; and, as will be understood, the steam-boiler and fire-box may be variously 40 constructed as to details.

In practical use the crown sheet of the fire-box is covered with water sufficiently to prevent over-heating of the crown sheet, and the piston valve is held at a distance from 45 the fusible element and permits the fusible element to be covered with water. In case the water becomes so low as to not afford protection to the fusible element, the fire-box heat entering the bore 11 melts the 50 fusible element, so that the metal of the latter flows down through the bore and into the fire-box, permitting steam, possibly mixed with water, to be forced through the opening 17 and at the same time permitting the 55 steam pressure in the steam-boiler and the water or steam entering the bore 15 to force the piston valve 21 and its stem slightly downward so that the bell-crank connected with the stem shall be operated and through 60 the remaining connections cause operation of the signal whistle, which will notify the engineer or attendant that the water has reached a dangerously low level and that the fusible element or "soft plug" has been 65 destroyed, an evidence of dangerously low

water which can not be obliterated under the usual conditions of operation. While the crown sheet is still sufficiently covered with water to safely permit feeding the boiler, the head 24 may be disconnected from the 70 bell-crank arm 26, after which the valve stem 20 may be pushed downward or permitted to descend until the piston valve becomes seated so as to close the opening 17, the piston valve being then held in place by 75 the steam pressure, after which the boiler may be fed with water to permit continuance of the trip to destination without further inconvenience, assuming that the steam boiler will be properly supplied with water, 80

Frequent inspection of fusible plugs in steam-boilers being required, the improved safety devices may be readily examined after withdrawing the plug 8 and the cylinder 14 through the crown sheet and away from 85 the piston valve, and releasing the fusible element if desired to further inspect it, and then a new element may be quickly inserted in place if required.

Having thus described the invention, what 90 is claimed as new is—

1. A low-water signal apparatus including a hollow plug, a fusible element removably seated upon the top of the plug, a hollow cylinder screwed onto the plug and having a valve seat ledge therein engaging the fusible element and securing it to the plug, the cylinder having an open unobstructed upper portion, a piston valve freely received into the upper portion of the cylinder and movable to the valve seat ledge on removal of the fusible element, and an operating-stem connected to the piston valve. 95

2. In low-water signal apparatus, the combination with a plug having a neck and a clear bore extending through the neck and the remainder of the plug, the neck and the remaining portion of the plug each having screw threads on the outer side thereof, and a fusible element on the top of the plug, of a hollow cylinder having a valve seat ledge on the inner side thereof and also screw threads extending from one end thereof toward the ledge to engage the screw threads on said neck and hold said ledge on said plug, the cylinder having a bore extending from the opposite end thereof to the ledge, a piston valve receivable into the top of the bore in the cylinder, and an operating-stem connected to the piston valve. 100

3. In low-water signal apparatus, the combination with a hollow plug and a fusible element on the top of the plug, of a hollow cylinder secured to the plug and having a valve seat ledge therein engaging the fusible element and securing it to the plug, the cylinder having a bore extending from its top to the ledge, a piston valve freely receivable into the bore in the cylinder, a stem connected to the valve and having a head secured 115 120 125 130

to its end and having also a stop collar thereon between said valve and said head, a standard, and a bell-crank pivoted to the standard and having an arm pivoted to said head, 5 the bell-crank having also a signal-operating arm thereon.

4. In a low-water signal apparatus, the combination with an operative signaling device, a hollow plug, and a fusible element on 10 the top of the hollow plug, of a hollow cylinder secured to the hollow plug and having an annular valve seat ledge integrally fixed therein engaging and securing the fusible element to the top of the hollow plug, a pis-

ton valve movable loosely in the cylinder 15 and adapted to contact with said ledge in the absence of the fusible element, said valve having a stem, a pivotally supported bell-crank pivotally connected with the valve stem, and a rod connected with the bell- 20 crank and signaling device.

In testimony whereof, I affix my signature in presence of two witnesses.

LEWIS NICHOLAS.
